(57) **CLAIM**

The ornamental design for a vehicle grille, as shown and described.

DESCRIPTION

FIG. 1 is a front perspective view of a vehicle grille attached to a vehicle, no part of the vehicle is claimed;

FIG. 2 is a perspective view of the vehicle grille;

FIG. 3 is a front elevation view of the vehicle grille;

FIG. 4 is a right side elevation view of the vehicle grille; and, FIG. 5 is a top plan view of the vehicle grille.

The broken lines are for illustrative purposes only and form no part of the claimed design.

The stippling indicates the curvature of the vehicle grille. The grille comprises three horizontal bar portions. The grille has a broad frontal profile and a thinner side profile. The side profile has an angular upward sweep.
